(57) CLAIM

We claim the ornamental design for a keyboard support with mouse pad, as shown and described.

DESCRIPTION

FIG. 1 is a perspective view of a keyboard support with mouse pad showing our new design, the broken lines are for illustrative purposes only and form no part of the claimed design;

FIG. 2 is a top plan view thereof;

FIG. 3 is a front elevation view thereof;

FIG. 4 is a right side elevation view thereof;

FIG. 5 is a rear elevation view thereof;

FIG. 6 is a left side elevation view thereof; and,

FIG. 7 is a bottom plan view thereof.

1 Claim, 7 Drawing SheetsFIG. 1.

FIG.2.

FIG. 3.

FIG. 4.

FIG. 7.
